UNITED STATES PATENT OFFICE.

LUDWIG R. ZEPKA, OF CLEVELAND, OHIO.

THEFT SIGNAL.

Application filed December 15, 1921. Serial No. 522,519.

To all whom it may concern:

Be it known that I, LUDWIG R. ZEPKA, citizen of the United States, residing at Cleveland, in the county of Cuyahoga and State of Ohio, have invented certain new and useful Improvements in Theft Signals, of which the following is a specification.

This invention relates to an improved theft signal for motor vehicles and seeks, 10 as one of its principal objects, to provide a device which may be conspicuously mounted permanently upon a vehicle for displaying a signal apprising the public when the vehicle is being operated by an unauthorized person.

A further object of the invention is to provide a signal employing a base and a detachable signal plate for displaying a signal and wherein, when it is not desired to 20 display the signal, the plate may be removed or detached from the base.

And the invention has as a still further object to provide a signal embodying means for automatically locking the signal plate 25 upon the base when inserted therein but wherein the signal plate cannot then be detached from the base without a proper key for releasing the plate.

Other and incidental objects will appear 30 hereinafter.

In the drawings:

Figure 1 is a rear elevation of my improved signal,

Figure 2 is a vertical sectional view 35 through the device,

Figure 3 is a horizontal sectional view on the line 3—3 of Figure 2, looking in the direction of the arrows,

Figure 4 is a vertical sectional view on 40 the line 4—4 of Figure 2, looking in the direction of the arrows,

Figure 5 is a vertical sectional view on the line 5—5 of Figure 2, looking in the direction of the arrows,

Figure 6 is a detail elevation of the catch plate and signal plate employed, the view illustrating the manner in which the signal plate is inserted in position,

Figure 7 is a perspective view showing 50 one of the securing pins or the base of the device,

Figure 8 is a fragmentary bottom plan view of the base,

Figure 9 is a horizontal sectional view 55 showing a slight modification of the invention,

Figure 10 is a vertical sectional view of the modified structure,

Figure 11 is a perspective view of a spacer block illustrated in connection with the 60 modified structure, and

Figure 12 is a fragmentary perspective view of the signal plate as employed in connection with the modified structure.

Referring now more particularly to Figures 1 to 8 inclusive of the drawings, I employ a base which is formed of a bottom section 10 and a mating cap section 11 fitting over the bottom section. At its ends, the cap section is provided with rearwardly 70 directed wings 12 and formed through both of the sections is a medial vertical slot 13 reduced in length near the upper face of the section 10 to define a pair of shoulders 14. In advance of the slot 13, the sections 75

are further provided with an internal recess 15 lying in parallel relation to the slot 13 and slidable in said recess is a catch plate 16. Communicating with the recess at one end thereof is a chamber 17 and disposed in 80 said chamber is a spring 18 coacting with the adjacent end of the plate. At the junction between the sections 10 and 11, the sections are provided with spaced laterally directed slots 19 extending from the slots 13 85

and fixed to the plate 16 are lateral pins 20 freely received in said slots. Confined between the sections at a point substantially midway between the slots 19, is an appropriate lock 21 extending rearwardly 90 through the rear side wall of the section 11 so that the lock key, as indicated at 22, may be readily inserted in the lock, and secured to the lock cylinder at its inner end is a crank 23 provided with a pin 24 freely 95

engaging in an opening 25 in the catch plate. Thus, the key 22 may be turned for rotating the lock cylinder and accordingly swinging the crank 23 to shift the catch plate endwise against the tension of the 100 spring 18. Formed through the sections 10 and 11 near the lower face of the former section, is a plurality of spaced horizontally disposed preferably square openings 26. As shown in Figure 105 6, the catch plate 16 is formed with a like number of registering slots 27, the rear end walls of which are straight. In practice, the device is mounted upon the wind shield of a vehicle to supplant the usual handle 110 upon the wind shield and I have, accordingly, in Figure 4, conventionally shown a

wind shield at 28. The bolts securing the usual handle as well as the handle itself, are first removed when the base is rested flat against the wind shield frame at its inner side and for then securing the base to the frame I provide a pair of securing pins 29. At their outer ends these pins are provided with heads to seat flat against the outer face of the wind shield frame while at their inner ends said pins are formed with beveled faces 30, the pins being provided with squared shanks to extend into a pair of the openings 26 in the base through the catch plate 16. Four of the openings 26 are provided since the spacing of the bolt openings in the wind shield frames of different vehicles may vary. As will be observed upon reference to Figure 6, the straight end walls of the slots 27 will normally intersect the openings 26 and the pins 29 are accordingly formed at their inner ends with the beveled faces 30 to engage said end walls of the slots for riding the catch plate endwise so that the pins may be readily pushed through the wind shield frame into the openings 26 into position. Formed in the section 10 of the base to intersect the openings 26 near their inner ends are, as shown in Figure 8, slots 31, at the outer ends of which are recesses 32 and freely received in said slots are locking screws 33 threaded into the inner end portions of the pins, the heads of the screws being accommodated in the recesses 32. As will be appreciated, the slots 31 will accommodate any variation in the thickness of different wind shield frames and embedding each of the screws 33 is a filler 34 concealing the screws. The pins 29 thus serve to rigidly connect the base to the wind shield frame while no means for releasing the pins will be visible. However, to effectually prevent removal of the pins, I provide said pins with notches 35 in which the straight end walls of the slots 27 of the catch plate 16 engage in the normal position of the plate. Accordingly, the catch plate will normally lock said pins against retraction. It is now to be noted that the wings 12 of the base may be readily grasped for manipulating the wind shield.

In conjunction with the base, I employ a signal plate 36 reduced at its lower margin to provide a tongue 37 adapted to freely fit in the slot 13 abutting the shoulders 14. This tongue is, as shown in Figure 2, provided with a central opening to fit over the lock 21 and formed in the tongue near its ends are substantially L-shaped slots 38 opening through the lower edge of the tongue. At the mouth of each of these slots, the lower edge of the tongue is cut away to provide a beveled face 39, the faces sloping toward one end of the tongue. Thus, the tongue of the plate may be inserted in the slot 13 to

engage the beveled faces 39 of the tongue with the pins 20 when, by pressing downwardly upon the plate, said faces will coat with the pins for shifting the catch plate 16 endwise against the tension of the spring 18 and riding the pins into the slots 38. The pins will then, of course, operate to securely lock the signal plate upon the base upstanding therefrom at the inner side of the wind shield 28. The plate, as suggested in Figure 1, carries a suitable warning indicating that the occupancy, starting, and driving of the vehicle, as well as tampering therewith, when the signal is displayed, is unauthorized so that, as will be seen, possibility of theft of a vehicle carrying the signal will be reduced to a minimum. When it is not desired to display the signal, the key 22 is inserted in the lock 21 and operated, as previously described, to retract the catch plate 16 when, as will be at once understood, the signal plate 36 may be lifted upwardly out of the slot 13 and removed.

Referring now to Figures 9 to 12 of the drawings, showing the modified form of the invention, it will be seen that I employ a base comprising sections 40 and 41 corresponding to the sections of the base of the preferred construction. The base is formed with a central vertical slot 42 corresponding to the slot 13 and slidably mounted in the base is a catch plate 43 corresponding to the plate 16. However, in the present instance, the plate 43 is, as shown in Figure 9, provided with spaced cam lugs 44 and slidably mounted in the base at right angles to said plate are pins 45 extending across the upper edge of the plate. These pins are formed with shoulders 46 normally abutting the plate and coacting with said shoulders are springs 47 normally holding the pins projected into the slot 42. A signal plate 48 is employed, this plate corresponding to the plate 36 of the preferred construction. At its lower margin the plate is provided with a tongue 49 freely fitting in the slot 42 and formed through the tongue are spaced openings 50 accommodating the pins 45. Below said openings the plate is, as shown in detail in Figure 12, provided with beveled faces 51 to coat with the outer ends of the pins. Accordingly, after the tongue 49 has been inserted in the slot 42 to engage the pins, downward pressure upon the plate will then serve to ride the beveled faces 51 over the adjacent ends of the pins for forcing the pins endwise against the tension of the springs 47. As the downward movement of the tongue 49 is thus continued, the openings 50 will be brought into register with the pins 45 when the springs 47 will serve to project the pins through said openings for thus locking the signal plate upon the base. The base carries an appropriate lock 52, as in the preferred construction, and secured to

the cylinder of this lock is a crank 53 corresponding to the crank 23 and coacting with the plate 43. Thus, by inserting a key in the lock and rotating the cylinder thereof, the plate 43 may be retracted against the spring tension thereon. As the plate is thus retracted, the cam lugs 44 will be caused to ride under the shoulders 46 of the pins 45 for retracting said pins to free the plate 48. 10 Thus, the plate may be readily inserted in position or removed while, under normal circumstances, the plate will be securely locked upon base. In this modification, the base is mounted upon a wind shield as in the 15 preferred construction and I have, accordingly, conventionally shown a wind shield at 54. In this instance, however, a wind shield having an oval frame is illustrated, and in order that the device may be readily attached to such a wind shield I provide a spacer strip 55 which is formed at one side with a concave face to seat against the wind shield frame and at its opposite side with a flat face to coact with the base of the device. Extending through the wind shield frame, the spacer strip, and into the base, 20 are securing pins 56, as in the preferred construction, these pins being held by screws 57 and being locked by the plate 43. Surrounding the pins to bear between the heads thereof and the outer face of the wind shield frame are washers 58 having concave inner sides to fit the frame while the outer sides of 25 said washers are flat to coact with the heads of the pins. As will be seen, this modified structure, like the preferred form of the invention, provides a highly efficient device for the purpose intended.

Having thus described the invention, what 30 is claimed as new is:

1. A theft signal including a base, attaching means therefor, a signal plate associated with the base, and means locking said attaching means against displacement and 45 provided with means locking the plate upon the base.

2. A theft signal including a base, a signal plate insertable therein, and a spring pressed catch plate upon the base having means for 50 automatically locking said signal plate upon the base when inserted therein.

3. A theft signal including a base, a signal plate insertable therein, a spring pressed catch upon the base for automatically locking 55 said plate upon the base when inserted

therein, and a lock carried by the base and operable for retracting said catch.

4. A theft signal including a base provided with a slot, a spring pressed catch upon the base having a pin intersecting said slot, and a signal plate insertable in the slot to coact with said pin to be detachably locked thereby upon the base. 60

5. A theft signal including a base provided with a slot, a spring pressed catch 65 upon the base having a pin intersecting said slot, a signal plate insertable in the slot to coact with said pin to be detachably locked thereby upon the base, and a lock upon the base having a cylinder provided with a crank 70 coacting with said catch and operable for retracting the catch.

6. A theft signal including a sectional base, a removable signal plate associated therewith, and means locking the sections 75 against separation and provided with means locking the plate upon the base.

7. A theft signal including a base, a spring pressed catch carried thereby, and a signal plate insertable in the base and provided 80 with means to coact with the catch for shifting the catch to engage the plate.

8. A theft signal including a base, a spring pressed catch having a locking pin, and a slotted signal plate insertable in the 85 base and provided with a beveled face to coact with said pin for shifting the catch to engage the pin in the slot of the plate.

9. A theft signal, including a base, an attaching pin extending into the base, the pin having a notch formed therein, a spring pressed catch upon the base normally engaging in said notch locking the pin against retraction, and a signal plate removably secured upon the base by said catch. 95

10. A theft signal including a sectional base, an attaching pin locking the sections against separation, a removable signal plate coacting with the base, and means locking the plate upon the base as well as also locking 100 said pin against displacement.

11. A theft signal including a sectional base, attaching means for the base securing the sections against separation, a removable signal plate coacting with the base, and means locking said attaching means against displacement and provided with means locking the plate upon the base. 105

In testimony whereof I affix my signature.
LUDWIG R. ZEPKA. [L. S.]
